(57) **CLAIM**

The ornamental design of an industrial robot control cabinet, as shown and described.

DESCRIPTION

FIG. 1 is a first embodiment, showing a front view of an industrial robot control cabinet of the new design;

FIG. 2 is a back view of the first embodiment;

FIG. 3 is a left view of the first embodiment;

FIG. 4 is a right view of the first embodiment;

FIG. 5 is a top view of the first embodiment;

FIG. 6 is a bottom view of the first embodiment; and,

FIG. 7 is a perspective view of the first embodiment.

Any broken line(s) shown are for illustrative purposes only and form no part of the claimed design.

1 Claim, 4 Drawing Sheets
